(57) CLAIM

The ornamental design for an animal collar, substantially as shown and described.

DESCRIPTION

FIG. 1 is a front perspective of an animal collar in accordance with our new design;

FIG. 2 is a front view thereof;

FIG. 3 is a back view thereof;

FIG. 4 is a left side view thereof;

FIG. 5 is a right side view thereof; and,

FIG. 6 is a top view of thereof, the bottom being a mirror image thereof.

The broken lines of the Figures are for illustrating portions of the animal collar that form no part of the claimed design.
